UNITED STATES PATENT OFFICE.

OLIVER N. EATON, OF NEW YORK, N. Y.

MOTIVE MECHANISM OR GEARING.

SPECIFICATION forming part of Letters Patent No. 258,728, dated May 30, 1882.

Application filed September 6, 1881. (No model.)

To all whom it may concern:

Be it known that I, OLIVER N. EATON, of the city of New York, in the county and State of New York, have invented a certain new and useful Motive Mechanism or Gearing, of which the following is a specification.

The chief object of my invention is to insure equal and uniform motive power in driving gear when two or more such gears are used to 10 actuate hoisting or similar machinery, and to provide an automatic means for such equalizing adjustment.

The scope of my invention includes its application to hoisting apparatus employing endless chains or ropes as a traveling ladder, and to all kinds of carriers employing two or more chains or ropes traveling upon or around pulleys or drums.

The instance of an endless-rope hoisting-ladder will sufficiently illustrate the application of my invention. It has always been an obstacle to the use of such an elevator that owing to one endless rope happening from any cause to be longer than the other, or to the enlargement 25 of the periphery of one pulley as compared with the other from accumulated dirt or other cause, one pulley would begin and continue to gain upon its companion and to drive its endless rope faster and faster until the 30 rounds connecting the rope sides of the ladder were at such an angle to the horizontal as to be useless for hanging anything on or until the rigidity of the right angles formed by the rounds and the sides of the endless ladder forced the leading rope to slip back upon the face of the faster pulley or lifted up the 35 lagging rope to the proper level. Equalization thus accomplished is necessarily attended by great strain, friction, and wear, and is uncertain in time and quantity of action. Where 40 endless ropes or chains are used as horizontal carriers and one travels faster than the other it tends to throw off to one side the things or material carried.

My invention also equalizes automatically and instantly the strain thrown upon the driving gearing or mechanism through the unequal transmission of motive power.

Referring to the accompanying drawings as 50 part of this specification, similar letters therein indicating similar parts, there is represented

in Figure 1 a front elevation of my invention as applied to an endless traveling ladder composed of two rope sides connected by rounds, and intended for hoisting purposes; and in Fig. 55 2 a plan of the same on the median line *x x*. Fig. 3 shows a sectional elevation on a median perpendicular line through the foregoing views. Fig. 5 shows a front elevation of a modification of Fig. 1, and Fig. 4 shows a sectional 60 elevation of Fig. 5 on a median perpendicular line.

A A are uprights on a suitable base framework, O O, having boxes for the shafts B and C. The shaft B here is supposed to receive 65 motion by any ordinary means—as a crank or pulley and belt, or spur-gearing—and to communicate this motion through the pinion F to the spur-wheel E, which is immovable upon the shaft C. This spur-wheel E carries the bevel-gear G, radially attached, as upon one of its arms or spokes as an axle, and free to revolve thereupon. The bevel-gear G may be attached to the shaft C by means of a collar keyed thereupon, and having an arm suited to serve as an axle for 70 the bevel-gear, as shown at P in Figs. 4 and 5. In this case motion may be communicated through a pinion, S, and spur-wheel T by means of cranks V V; or any other of the ordinary means of applying power and transmitting motion 75 80 may be adopted. This bevel-gear engages at opposite sides the bevel-gears H H', respectively connected by sleeves I I' with the actuating or driving pulleys D D', all loosely hung on the shaft C. Upon these pulleys D D' and 85 similar pulleys, K K', on the shaft L, which has bearings on a suitable frame-work, M M, properly located, the endless ropes R R' travel, and these ropes are connected by rounds J J, affixed by clips or any ordinary means. 90

The manner of operation is as follows: When the spur-wheel E is set in motion it carries with it, during revolution, the bevel-gear G, which thus communicates equal motion to the bevel-gears H H', which, by their connecting-sleeves I I', in turn communicate equal motion to the driving-pulleys D D', and through them to the endless ladder itself. When the shaft C in Figs. 4 and 5 is set in motion through the spur-gearing or otherwise it revolves the 95 arm or axle P and the bevel-gear G about a common center, and this bevel-gear, during 100

revolution, engaging on opposite sides the bevel-gears H H' and their connections, consequently communicates equal motion to them similarly, as just explained. With such an arrangement of moving parts, if the rope R' , for example, runs faster than its companion rope, R , from any cause, there immediately results a tendency to close the right angles d, h, a , and e to acute angles, and to open the right angles c, g, b , and f to obtuse angles, which tendency is resisted by the rigidity of the natural angle, and the resistance is proportionate to the number of angles and amount of strain, and is immediately felt by the driving-pulley D' , which is thereby turned backward upon the shaft C and itself correspondingly revolves the bevel-gear H' through the connecting-sleeve I' , and thus causes a supplementary revolution of the bevel-gear G , which in its turn causes the bevel-gear H and through the connecting-sleeve I the driving-pulley D to move a corresponding distance in the opposite direction. The driving-pulley D is thus accelerated until it is equal in speed and power with its fellow; or the faster rope may be regarded as lifting up its lagging companion by the rigidity of the right angles a, b, c , and d and e, f, g , and h , the peculiar location and movement of the equalizing-gearing permitting the necessary reciprocal movement of the driving-pulleys. The practical effect, however, is the same, and automatic and instant adjustment is completely secured. The sleeves I I' are introduced to occupy intervening space and to obviate the necessity of having the gear-wheel G of large diameter, which might mar the true proportion of the machinery. It is obvious that the same desideratum may be reached by inter-

posing in a line on the shaft C an odd number of suitable gear-wheels, the outside members 40 of the series finally engaging suitable gearing upon the driving-pulleys. This mechanism obviates the slipping of the ropes upon the faces of the pulleys, which is always attended with great friction and wear, and is only consequent 45 upon great contortion. This construction keeps the rounds always horizontal, the traveling ropes at the same rate of speed, and the strain and motive power of the driving-pulleys exactly equal. 50

I claim and desire to secure by Letters Patent—

1. In motive mechanism or gearing, the arrangement of two actuating or driving pulleys or drums connected together by interposed 55 gearing for the purpose and in the manner substantially as set forth.
2. In motive mechanism or gearing, the combination of two or more driving or winding pulleys or drums connected by interposed 60 gearing whereby these motive pulleys or drums are allowed reciprocal movement to compensate for unequal motion.
3. In motive mechanism or gearing, a driving-gear bearing radially gearing suited to 65 communicate motion to and allow reciprocal movement of actuating pulleys or drums on each side.

In testimony whereof I have hereunto signed my name this 2d day of September, A. D. 1881, 70 in the presence of two subscribing witnesses.

OLIVER N. EATON.
